UNITED STATES PATENT OFFICE.

FRANK WELLS WEED AND JACOB FRANKLIN CLOW, OF POTSDAM,
NEW YORK.

NON-REFILLABLE BOTTLE.

SPECIFICATION forming part of Letters Patent No. 687,509, dated November 26, 1901.

Application filed July 20, 1901. Serial No. 69,014. (No model.)

To all whom it may concern:

Be it known that we, FRANK WELLS WEED and JACOB FRANKLIN CLOW, residing at Potsdam, in the county of St. Lawrence and State 5 of New York, have invented certain new and useful Improvements in Non-Refillable Bottles, of which the following is a full, clear, and exact description, such as will enable others skilled in the art to which it appertains 10 to make and use the same.

Our invention relates to improvements in bottles, and especially to that class of bottles known as "non-refillable."

The objects of our invention are to provide 15 the mouth of a bottle with a device which will permit the liquid contained in the bottle to be poured therefrom, but will prevent the bottle being refilled, and which device cannot be removed from the bottle without breaking 20 the top or the neck of the bottle; also, to obtain patent on the neck of the bottle itself. We attain these objects by the device illustrated in the accompanying drawings, in which—

25 Figure 1 is a vertical longitudinal section of the neck of a bottle, showing our non-refillable device in place, the bottle being in an upright position. Fig. 2 is a section taken on the same plane as in Fig. 1, the bottle being 30 turned to show the position of the valve or plunger while the liquid is being poured from the bottle. Fig. 3 is a section on line 33 of Fig. 1 looking in the direction of the arrow, and Fig. 4 is a detail perspective view 35 of the plug and guard.

Similar letters and numerals of reference refer to similar parts throughout the several views.

The part lettered A represents the neck of 40 a bottle, which has a groove 1 formed in the inside thereof.

2 is a sleeve or casing, internally screw-threaded at 3, having on the outside at opposite points springs 4. The upper end of this 45 casing has attached thereto a flanged disk 5, which has an opening 6 therein.

B is the stopper proper, and consists of a screw-threaded plug 7, having an opening 8 therein, through which is inserted the plunger 9, closed at the top, but having an opening 50 or passage 10 through the center thereof

and also two lateral openings 11 in the sides thereof under the top or cap 12. The under face 13 of the cap of the plug is ground and fits into a ground seat 14 on the upper part 55 of the plug 7. Connected to the plug by pieces or strips 15 is what may be termed a "guard" C. This guard consists of a short section of tube or pipe 16, cut on a bevel, as shown in the drawings. Connected to the lower part 60 of this tube, just inside thereof, is a baffle-plate 17, which extends more than half-way across the opening in the tube. 18 is another baffle-plate that extends in the opposite direction and also more than half across the 65 opening in the tube, so that the two plates overlap. The object of this construction is to prevent tampering with the plug. By this arrangement a wire or other device cannot be inserted in the bottle under the plunger 70 to hold the plunger off its seat to refill the bottle. The tube or guard is placed at such a distance from the plug 7 that the lower baffle-plate 17 will prevent the plunger from falling out of the plug when the bottle is turned 75 over or inverted, the upper end or cap of the plunger coming into contact with this baffle-plate when the bottle is in turned-over position, as shown in Fig. 2.

The plug carrying the guard is inserted into 80 the lower end of the shell and screw-threaded in place, as shown. The device is then ready to be inserted in the bottle. When the bottle is filled with the desired material, the sleeve carrying the plug and the guard is 85 pushed down into the neck of the bottle until the springs 4 snap into the grooves 1, when the non-refillable device is held in place and cannot be removed without breaking the neck of the bottle. When the bottle is in an up- 90 right position, as shown in Fig. 1, the plunger 9 fits down on the seat 14 of the plug and acts as a stopper or closure for the bottle. When it is desired to pour out the contents of the bottle, it is upset or turned, as shown 95 in Fig. 2, the plunger 9 being fitted loosely in the plug and will by its own weight drop down into the position shown in Fig. 2, and it will be prevented from falling out of the plug by the baffle-plate 17, the liquid in the 100 bottle passing out through the opening 10 in the plunger, through the wing-passages 11,

and through or around the baffle-plates 17 and 18, and out of the bottle in the direction shown by the arrows in Fig. 2. When as much of the liquid in the bottle as desired is poured out, as described, the bottle is placed in an upright position, when the plug will immediately fall to its seat, as shown in Fig. 1. When in this position, the plunger completely closes the bottle and prevents any liquid from being poured into the bottle.

By our invention the refilling of a bottle is effectually prevented, and this non-refillable device cannot be tampered with. It cannot be removed from the bottle without the bottle being broken.

Having now described our invention, what we claim as new, and desire to secure by Letters Patent, is—

1. In a device for preventing the refilling of a bottle, a sleeve or casing having springs on each side thereof adapted to fit in a groove in the neck of the bottle, a plug screw-threaded in one end of the sleeve and having an opening therein, the upper face of the plug being ground to form a seat for a plunger, a plunger having an opening through the center thereof and two wing-openings in the sides thereof for the passage of the liquid, a cap or top on the end of the plunger having a ground face which coacts with the ground seat of the plug and when in place closes the opening in the plug, a guard above the plug and placed at such a distance therefrom as to prevent the plunger from falling out of the plug when the device is inverted.

2. In a device for preventing the refilling of a bottle, a sleeve or casing having springs adapted to fit into a groove in the neck of the bottle, a plug screw-threaded in the sleeve and having an opening therethrough; the upper face of the plug being ground to form a seat for a plunger, a plunger having an opening through the center thereof and an opening in the side thereof as passages for the contents of the bottle when the bottle is being emptied, a cap or top on the upper end of the plunger having a ground face which coacts with the ground face of the plug, the cap and plunger acting as a closure for the opening in the plug when the plunger is in its seat,

strips attached to the plug, a section of tube or pipe connected to the upper ends of the strips, overlapping baffle-plates in the tube, the under baffle-plate being placed at such a distance from the plug as will prevent the plunger from falling out of the plug.

3. In a device for preventing the refilling of a bottle, a sleeve or casing having springs on each side thereof adapted to fit in a groove in the neck of a bottle, a plug seated in one end of the sleeve and having an opening therein, the upper face thereof being ground to form a seat for a plunger, a plunger having an opening through the center thereof and also openings in the sides for the passage of a liquid, the top or upper end of the plunger being closed and having a ground face on the upper end thereof which acts with the ground seat of the plug and when in place closes the opening in the plug, a guard above the plug and connected directly therewith and placed at such a distance therefrom as to prevent the plunger from falling out of the plug when the device of the bottle to which it is attached is inverted.

4. In a non-refillable bottle, the combination with the neck of the bottle having a groove formed in the side thereof, of a non-refillable stopper comprising a sleeve having a spring adapted to fit in the groove when the stopper is in place, a plug screw-threaded in the lower end of the sleeve and having a cylindrical opening therethrough, a plunger operating loosely in the plug, the said plunger being closed at its upper end but having a passage through the center and the walls thereof, the upper face of the plunger coacting to form a tight joint when the plunger is seated on the plug, a guard above the plunger and at such a distance from the plug that the plunger will be retained in the plug when the bottle is inverted.

In testimony whereof we affix our signatures in the presence of two witnesses.

FRANK WELLS WEED.
JACOB FRANKLIN CLOW.
